UNITED STATES PATENT OFFICE.

CHARLES M. HEUBLEIN, OF CHICAGO, ILLINOIS.

WINDOW ATTACHMENT.

Application filed May 14, 1926. Serial No. 109,174.

This invention relates to certain novel improvements in window attachments and more especially to a device for raising the lower end portion of a window curtain 5 above an opening provided by raising the lower window sash of a window construction and has for its principal object the provision of an improved construction of this character which will be highly efficient 10 in use and economical in manufacture.

The present invention constitutes an improvement over that disclosed in my prior application filed in the United States Patent Office on or about the second day of 15 February, 1926, Ser. No. 85,585.

The present invention contemplates the provision of a curtain engaging member movable in engagement with a portion of a window curtain, by movement of a window 20 sash of a window construction, in an upward direction to elevate the lower end portion of the window curtain above an opening provided by raising the lower window sash of the window construction.

25 Other objects will appear hereinafter.

The invention consists in the novel combination and arrangement of parts to be hereinafter described and claimed.

The invention will be best understood by 30 reference to the accompanying drawings showing the preferred form of construction, and in which:

Fig. 1 is an elevational view of a window construction illustrating the invention associated therewith,

35 Fig. 2 is a sectional detail view of the same taken substantially on line 2—2 of Fig. 1 illustrating the window curtain in raised position,

40 Fig. 3 is a sectional detail view of the same taken substantially on line 3—3 of Fig. 2,

Fig. 4 is an enlarged elevational view, 45 partly in section, of the attachment embodying the invention,

Fig. 5 is a fragmentary sectional detail view of the same taken substantially on line 5—5 of Fig. 4, and

Fig. 6 is a fragmentary sectional detail 50 view of the same taken substantially on line 6—6 of Fig. 4.

To accomplish the various objects of the present invention I provide guide plates 10, as shown in Figure 5, substantially U-shaped 55 in cross-section, secured as at 11, Figs. 3

and 4, to the lower window sash guide rails 12 of a window construction 13. These guide plates include longitudinally extending recesses 14 formed in the side walls 15 of the guide plates, as best illustrated in 60 Fig. 3.

The lower end portions of the bight portions 16 of the guide plates are cut away to provide passages 17 and curved inwardly as at 18, Fig. 4, to provide rounded bearing 65 edges 19.

Mounted for movement between the guide plates within the opposite wall portions 15 and 15' are carrying arms 20. These arms 20 carry at their inner end portions bearing screws 21 rotatably supporting rollers 22 which are adapted to work in the recesses 14. The arms have arcuate slots 23 defined by lines 24 concentric with the axis of the bearing screws to define curved fingers 25, 70 Fig. 4. The outer end portions 26 of the fingers 25 carry rollers 27 for the purpose of reducing friction when the rollers work along the inner wall surface 28 of the bight portions 16 of the guide plates 10. 80

Carried by the corner portions 29 of the lower window sash 30 of the window construction 13 are operating arms 31 including laterally extending portions 32. These laterally extending portions 32 are slotted as 85 at 33 and working within these slots are rotatable sleeves 34 carried by bearing screws 35 in turn carried by the arms 20 as best illustrated in Figs. 5 and 6. The outer end portions 36 of the arms 20 carry a rod 37 90 adapted to move in engagement with the lower end portion 38 of the window curtain 39 for reasons hereinafter understood.

The operation of the device thus far set forth is as follows:

When the window curtain 39 is hung in a straight line before the window structure 10 the arms 20 are disposed in their lowermost position, as best illustrated in Fig. 4, with the rod 37 in position to engage with 100 the lower end portion 38 of the window curtain. When the arms are in this position the lower window sash 30 is likewise in its closed position.

When the window sash 30 is raised from 105 its closed position, this raising movement of the window sash imparts movement to the operating arms 31. As these operating arms 31 move with the window sash 30 their laterally extending portions 32 act upon the 110

rotatable sleeves 34 and cause an outward and upward pivotal movement of the arms 20. As these arms 20 pivot in this direction the edge portions 18' of the arcuated slots 5 30 work around and under the rounded edge portions 18. During this pivotal movement of the arms 20 the rod 37 is in contact with an adjacent portion of the window curtain 39 to fold its lower end, as shown in Figure 10 2. This pivotal movement of the arms 20 in this direction continues until the fingers 25 are moved inwardly of the rounded edge portions 18 at which time the rotatable sleeves are disposed in engagement with the 15 longitudinal edge portions 19' of the wall portion 15. When the arms 20 have reached this position continued upward movement of the window sash urges the operating arms 31 to act upon the rotatable sleeves 34 and 20 move the arms 20 in a vertical direction with the rollers 27 riding over the inner surfaces 28 of the bight portions of the guide plates and with the rotatable sleeves 34 bearing upon the edges 19'. During this upward 25 movement of the arms 20, through the raising action of the sash 30, the rollers 22 work in the recesses 14 serving to guide the arms 20 in their vertical movement. The rollers 22 and screws 21 provide a pivotal connection 30 as well as a slidable connection between the arms 20 and the guide plates.

When the window sash 30 is closed the arms 20 are caused to move downwardly in a vertical direction until the rollers 27 work 35 outwardly over the rounded edge portions 18 at which time pivotal movement is urged to the arms 20. During this pivotal movement the rounded edge portions 18 pass into the arcuated slots 23 as best illustrated in Fig. 4. This latter pivotal movement of the arms 20 brings the rod 37 in position to permit the window curtain to hang in a straight line before the window construction.

One feature of the present invention 45 which enables me to manufacture the device at a economical cost resides in the manner in which the guide plates are formed. As is apparent from the description herein and with reference to the accompanying drawings these guides plates are formed from a sheet of material bent substantially U-shaped to define the guide ways 16' within 50 which the arms 20 work and likewise to define the recesses 14.

It will be noted in Fig. 1 of the drawings 55 that the rod 37 is located a predetermined distance above the top sash rail 37' whereby when this rod 37 is in its lowermost position the same will not interfere with the raising 60 of the lower window sash, said rod 37 being illustrated in this figure as well as Fig. 2 of the drawings in its uppermost pivotal movement in a position ready for vertical movement.

65 While I have illustrated and described the

preferred form of construction for carrying my invention into effect, this is capable of variation and modification without departing from the spirit of the invention. I, therefore, do not wish to be limited to the 70 precise details of construction set forth, but desire to avail myself of such variations and modifications as come within the scope of the appended claims.

Having thus set forth my invention, what 75 I claim as new and desire to secure by Letters-Patent is:

1. A window attachment including the combination with a window construction and a movable sash of the window construction, of substantially U-shaped guide plates secured to the window construction and including passages at their lower end portions, supporting arms including slotted end portions defining fingers movable longitudinally 80 within the guide plates, the slots of the slotted end portions being adapted to receive edge portions of the guide plates defining a passage when said supporting arms are pivoted in a certain direction and the fingers 85 defined at said end portions being adapted for bearing relation with the bight portions of the U-shaped guide plates when the supporting arms are moved in a longitudinal direction with respect to the guide plates 90 for limiting pivotal movement of the supporting arms when moved in said direction, means providing a slidable pivotal connection between the supporting arms and the guide plates, a curtain engaging member 95 carried by the supporting arms, and means carried for movement with the window sash and operable upon the supporting arms for pivoting the supporting arms into and out of position for movement longitudinally of 100 the guide plates.

2. In a window attachment for a window construction, the combination with a curtain engaging rod movable into engagement with a window curtain, arms movable longitudinally of the window construction and supporting the rod, guide members carried by the arms, means for moving the arms longitudinally of the window construction, of guiding plates for the arms, said guiding 110 plates each being formed from a sheet of material bent substantially U-shaped and provided with a wall portion having a longitudinal recess formed therein receiving the 115 guide member adjacent thereto.

3. In a window attachment for a window construction, the combination with a curtain engaging rod movable into engagement with a window curtain, arms movable longitudinally of the window construction and supporting the rod, of guide plates for the arms, said guide plates each being formed from a sheet of material bent substantially U-shaped and provided with a wall portion 125 having a recess formed therein, and a guide 130

member carried by each of the arms and working in the recesses and providing a slide-
able and pivotal connection between the arm
and guide plate.

- 5 4. A curtain operating attachment for a
window having a vertically movable sash,
which includes a swinging frame adapted to
engage the intermediate portion of the curtain
hanging in front of said sash, an arm 25
10 for said frame, a vertical guide member
mounted on the window frame, a longitudinal
channel in said guide, a roller on said
arm adapted to ride in said channel, means
associated with the movable window sash, 30
15 for imparting an initial rotation of said arm
about the axis of said roller, in response to
upward movement of said sash and means
for releasing said arm for upward move-
ment with said sash after a predetermined 35
20 initial rotary movement.

5. A curtain operating attachment for a

window having a vertically movable sash,
which includes a swinging frame adapted
to engage the intermediate portion of the
curtain hanging in front of said sash, an arm 25
for said frame, a vertical guide member
mounted on the window frame, a longitudinal
channel in said guide, a roller on said
arm adapted to ride in said channel, means
associated with the movable window sash, 30
for imparting an initial rotation of said arm
about the axis of said roller, in response to
upward movement of said sash and means
for releasing said arm for upward move-
ment with said sash after a predetermined 35
initial rotary movement, and a roller at the
inner end of said arm, adapted to engage
said vertical guide member during the up-
ward movement of the frame after said in-
initial rotary movement. 40

In testimony whereof I affix my signature.
CHARLES M. HEUBLEIN.
